BOMB DROPPING TOY AIRPLANE

Gerald C. Kelly, Apponaug, R. I.

Application December 16, 1948, Serial No. 65,611

3 Claims. (Cl. 273—95)

1

My invention relates to improvements in toy airplanes.

I am aware that others have provided toy airplanes in which a stick, carried by the hand of the operator, having its upper end attached by a cord to the airplane, is rotated by the arm of the operator to cause the airplane to rotate in a circular course around his hand. This has necessitated that the arm of the operator be at all times in a raised position and that the hand be continuously rotated to propel the airplane in its flight. Such devices are very tedious to operate as the hand must be held erect and moved during the entire operation and it has been impossible to take off the airplane or land it from the ground or to successfully make it dive, climb or loop.

An essential feature of my invention comprises the use of a pole, preferably of a height substantially greater than that of the operator, having the model airplane so attached to the upper end of the pole by a cord which is mounted so that its pole attaching portion or means freely rotates about the upper end of the pole, whereby the lower end of said pole may be rested on the ground, its upper end tilted and rotated by the hand of the operator to cause said airplane to take off from the ground and rotate in a banked position around said pole a substantial distance above the ground until it gains flying momentum when said airplane may fly in a banked position by its own inertia on said ring around the then erect upper end of said pole and land evenly, or continue its flight on intermittent rotations of the upper end of the pole, or by rotating said upper end in an elliptical orbit, said airplane may dive and turn and climb in flight.

An object of my invention, therefore, is to provide a toy of this description, in which the model airplane may take off from and land on the ground as in actual practice.

A further object of my invention is to provide a device of this description which is very easy to operate as the weight of the structure is entirely carried by the ground and all that the operator has to do is to revolve the upper end of the pole, requiring a minimum amount of effort, not sufficient to tire the operator.

A further object of my invention is to provide a device wherein after the upper end of the pole has been rotated to permit the airplane to gain flying momentum, said airplane may fly around the then erect upper end of the pole by its own inertia for a substantial number of revolutions, so that during the larger portion of its flight no

2

exertion on the part of the operator is required at all.

A further object of my invention is to provide a device in which, as soon as the airplane starts to lose flying momentum, it may land evenly on the ground in simulation of an airplane or may continue its flight almost indefinitely by the application of a few short intermittent rotations of the upper end of the pole to gain flying momentum.

A further object of my invention is to provide a device in which the upper end of the pole may be rotated in an elliptical orbit to cause the airplane to dive and climb in flight in simulation of an actual airplane.

A further object of my invention is to provide the pole and model airplane of such a weight that the pole may be lifted off the ground and rotated in an oblique plane above the horizontal to cause said plane to do an inside loop.

A further feature of my invention relates to the provision of a unique type of bombing device operable by a finger of the hand of the operator which rotates the pole, including a bomb rack on the plane and a manual actuator therefor on the pole effective for releasing a bomb at a time from said bomb rack.

Further features of my invention relate to the actual construction of the model airplane and pole I specifically employ, and include improvements in the nose and landing gear of the airplane.

A further feature of my invention resides in the fact that I preferably connect the operating cord from the pole to a point on said airplane slightly interior of its center of gravity in its direction of rotation, so that the plane will automatically be banked as it rotates around the upper end of the pole of the operator at a height clearly free of the operator.

These and such other objects of my invention as may hereinafter appear will be best understood from a description of the accompanying drawings which illustrate an embodiment thereof.

Fig. 1 is a diagrammatic perspective view showing my invention in use, being operated by the arm of an operator, showing the pole, cord and airplane in full lines in a take-off position and in dotted lines in a flying position.

Fig. 2 is a side elevation partially shown in section of the upper end of the pole.

Fig. 3 is a side elevation of the model airplane partially broken away and shown in section, Figs.

2 and 3 being illustrative of the airplane in its take-off position.

Fig. 4 is a reverse plan view showing how the two rear wheels of the landing gear are attached to the model airplane.

Fig. 5 is a diagrammatic front elevation showing how the front landing wheel is attached to the model airplane.

Fig. 6 is a side elevational view of the pole similar to Fig. 2, but showing the parts in bomb dropping position.

Fig. 7 is a side elevation like Fig. 3 in bomb dropping position, Figs. 6 and 7 showing the positions of all parts of the airplane toy in a bomb dropping position.

Fig. 8 is a side elevation of the upper end of the pole taken at right angles to Figs. 2 and 6, showing the position the movable parts assume in operation, as shown in Figs. 2 and 3 in full lines and the position said parts assume in bomb dropping position as shown in Figs. 6 and 7 in dotted lines.

Fig. 9 is a transverse vertical sectional view taken along the line 9—9 of Fig. 7.

Fig. 10 is a diagrammatic plan view showing how the upper end of the pole is initially rotated in spiral formation to move the plane from take-off to flying position, and then rotated in the circle shown to gain flying momentum when the upper end of the pole may be held erect to permit the plane to fly of its own inertia.

In the drawings, wherein like characters of reference generally indicate like parts throughout, 20 generally indicates a toy constructed in accordance with my invention. Said toy includes a pole 22 of a height substantially greater than that of the operator 24. Said pole preferably has a ring 26 freely rotatably mounted on the upper end 28 thereof. I provide the model airplane 30 and a cord 33 joining said model airplane 30 to said ring 26, whereby the lower end 32 of said pole may be rested on the ground 34, the plane 30 laid on the ground in take-off position and the upper end of the pole tilted and rotated by the hand of the operator to cause said airplane to take off from the ground and rotate around said pole 22 and operator 24 a substantial distance above the ground until it gains flying momentum when the pole may be held erect and said airplane may fly by its own inertia around said pole and when its flying momentum has become expended, land evenly in simulation of an ordinary airplane, or it may, on intermittent rotations of the upper end 28 of the pole to again provide flying momentum, continue its flight through its own inertia. If desired, the pole 22 and model airplane 30 may be of such a weight that the pole may be grasped by both hands of the operator and rotated in an oblique plane above the horizontal to cause said plane to loop. It is also apparent that if the upper end 28 of the pole be rotated in an elliptical orbit by the hand 36 and arm 38 of the operator, that said plane may dive, turn and climb, in flight.

I also provide a bomb rack 40 mounted on the model airplane 30, preferably vertically, and I provide a succession of bombs 42 vertically superimposed on each other within said rack and manually movable means, including the cord 84 mounted on and connected to said pole and airplane for successively releasing a bomb 42 at a time from said bomb rack.

In practice, the upper end 28 of the pole is provided with the axial hole 44 therein, and I provide a hollow cylindrical bearing 46 having its

lower end mounted in said hole and a stop comprising an outwardly flaring portion 48 on the upper end thereof. The ring 26 comprises a ring shaped member rotatably mounted on said bearing 46, having an eyelet 50 therein for securement of the upper end 52 of the cord 33 therein. The lower end of said cord is secured to an eyelet 53 mounted on the upper end of the fuselage 60 of said airplane, preferably at a point interior of the center of gravity of said airplane in its direction of rotation, in the embodiment shown preferably at an angle of 5° inwardly of the vertical line 61 passing through the center of gravity, when in raised position. (See Fig. 9.)

The model airplane is provided with a bomb releasing means; the bombs 42 are preferably of a generally cylindrical shape and are provided with an extended reduced center portion 54, providing the cylindrical tips 56 at each end thereof, so that each bomb is of the general shape of a dumbbell, with the exception that the ends thereof are cylindrical instead of spherical.

The bomb releasing means in the model airplane comprises a cylindrical bomb rack 40 mounted in a hole 58 extending substantially vertically of the fuselage or body 60 of the airplane. Said cylindrical bomb rack 40 has an internal periphery of a size to receive a succession of vertically superimposed bombs 42 therein, and is provided with the open upper end 62 and open lower end 64 in an extension 66 projecting below the fuselage 60. Said extension 66 has a peripheral slot 68 therein on the rear surface thereof substantially the height of one and one-half bombs from the lower end thereof adjacent the lower surface of the body.

To actually release a bomb, I provide a releasing lever 70 of the first class of a length substantially the distance between said rack lower end 64 and slot 68, having a pivot ear 72 substantially centrally thereof for pivotal mounting on a pivot lug 74 extending rearwardly from said rack extension 66 by means of the pivot pin 76.

Said lever 70 is provided with a lower inwardly projecting arm 78 adapted to underlie said lower end 64 of the bomb rack 40 and to support the aligned bombs 42 in the rack 40 and an upper inwardly projecting arm 80 pivotal to a position within said slot 68, in the embodiment shown both arms 78 and 80 projecting forwardly for this purpose.

I provide manually movable means connected with said pole 22 to tilt the lower end 78 of said lever outwardly to release a bomb, causing said upper end 80 to move within said slot 68 to underlie the upper end of the next adjacent bomb, said means comprising an eye 82 projecting outwardly, in the embodiment shown rearwardly from the lower end 78 of said lever, and the operating cord 84 extending upwardly through a vertical slot 86 therefor provided in said fuselage and to the upper end of said pole and operable by the hand of the operator in the manner to be described.

I also provide spring means 88 operable on release of said manually movable means 84 to tilt said lever 70 back to a position withdrawing its upper arm 80 from said slot 68, permitting the bombs 42 in said rack to drop, with the lower end 78 of said lever covering the open end 64 of said bomb rack 40 to abut the lower end of the then bottom bomb to retain it in a cocked position on said rack with the pile of bombs superimposed above it.

In the embodiment shown, said spring comprises a coil spring having its upper end 90

wrapped around a lug 92 projecting laterally from the pivot lug 74 and its lower end 93 coiled around the lower portion of the lever 70.

While any means may be provided on said pole for raising said cord 84 to tilt the lever 70 to release a bomb 42 as shown in Fig. 7, in my preferred embodiment shown, said means is preferably constructed as follows:

The axial hole 44 has a reduced portion 92 extending a substantial distance downwardly from said bearing 46 and a radial slot 94 extending an equal distance axially of said pole.

To raise the bomb operating cord 84, I provide a bomb operating rod 96 of substantial length, having an upper end 98 extending axially through the hollow bearing 46 and axial hole extension 92, a portion 100 projecting radially outwardly through said axial slot 94 and a lower portion 102 extending axially downwardly to adjacent the height of the operator. To maintain said lower portion 102 in alignment, I provide the spaced upper guide eyelet 104 and lower guide eyelet 106. Said operating rod 96 is adapted to be raised to raise the cord 84 for actuating the bomb releasing lever 70 by the manually operated means to be described, and I provide the spring 108 to assist in returning it to starting position, comprising the coil spring 108, having its upper end secured to said radial portion 100 and its lower end secured to the upper eyelet 104. I also mount the aligned eyelets 109 and 110 on said pole 22 diametrically opposite said lower rod end 102, with the upper eyelet 109 a substantial distance above the tip of said lower end 102, and I provide the looped cord 112 having one end thereof connected to the tip of said lower rod end 102 and having each portion 114 of the loop extending around diametrically opposite sides of said pole 22 and extending jointly downwardly through said opposite aligned eyelets 109 and 110, and I provide a finger operable ring 116 on the lower end of said cord 112. I mount the stop nut 118 on the upper end of said rod 98 and I rotatably mount the ring 120 on the upper end of said rod, being preferably supported by another stop nut 122 mounted on said rod below the desired position of said ring 120. Said ring 120 is also provided with an eyelet 124 for receiving the upper end of the operating cord 84.

For the purpose of my invention hitherto described any type of model airplane may be employed. I preferably, however, construct my improved model airplane particularly for use in the aforescribed combination and for this purpose make the fuselage of the usual conical shape having tapered ends and attach the rudder 126 thereto.

In my preferred embodiment, the lower end of the fuselage is provided with the elongated transverse slot 128 for receiving the central portion of the one piece wing member 131 transversely therethrough. For a purpose to be described, I also provide the front axle receiving transverse slot 130 extending rearwardly beneath the nose 132 thereof. To suitably balance the airplane in its flight, I provide the metal ring 134 fitted on the tip of the nose 132 above said slot 130 and I mount the free spinning propeller 136 on said nose, preferably on a suitable screw 138 projecting centrally rearwardly thereof.

I provide a landing gear for my toy airplane, made essentially of bent wire. For this purpose, I provide a rear axle 140 made of bent wire, having a landing wheel 142 mounted on each end thereof and a central prong 144 of substantial

width projecting first rearwardly, then upwardly, and having a preferably W-shaped portion 146 projecting forwardly within said transverse slot 128. The transverse wing member 131 is then mounted within said slot 128 and suitably secured thereto by means of the screws 129, securing said axle prong 144 and hence rear axle bar 140 to said model airplane. The front axle 147 has a transverse portion 148 on which the front wheel 150 is rotatably mounted and the arms 152 projecting obliquely upwardly and forwardly from each end thereof to cross each other and have rearwardly extending tips 154 fitting into opposite ends of said rearwardly extending nose slot 130. It is obvious, however, that in place of the specific landing gear shown any suitable type of landing gear may be employed.

If desired the pole 22 may be made in the detachable portions 22a and 22b, which may be joined together by the connecting sleeve 21 shown in section in Fig. 6.

The operation of my improved device is obvious from the above description. The airplane 30 is rested on the ground in a position, so that when the upper end 28 of the pole is held in position by the hand 35 and arm 38 of the operator 24, the cords 33 and 84 will be positively taut. The upper end 28 of the pole is then swung in a spiral course diagrammatically illustrated in Fig. 10 until it attains the circle 27 shown therein when it may be rotated on the circle until the model airplane gains the desired flying momentum. The airplane will then attain a position substantially even with the shoulders of the operator or even higher as diagrammatically illustrated in dotted lines in Fig. 1, when if the upper end 28 of the pole is held erect, the airplane will rotate in a banked position of its own flying momentum around the top of the pole and if the top of the pole be no longer rotated, it will slowly lose its flying momentum and land evenly, both the take-off and landing being actually simulative of that of a real airplane. If it be desired to continue the flying longer, as soon as the flying airplane starts to lose momentum, the upper end of the pole 28 may again be rotated a few turns in a circular path 27 as shown in Fig. 10, causing the airplane to again attain flying momentum. The plane can continue its flight as long as the operator desires, it being a very easy plane to fly as the operator does not have to lift the weight of anything, the entire weight of the device being supported by the lower end 32 of the pole resting upon the ground. It is only necessary to rotate the pole a few turns and the airplane will coast fifteen times in half a minute, when the pole may again be rotated four or five times in five seconds to cause the plane to continue to fly almost indefinitely. Due to the fact that the eyelet 53 is mounted interior of the center of gravity of the model airplane, the plane will fly in perfect banked alignment around and around. Should it be desired to cause the plane to climb, turn and dive successively, the upper end of the pole may be rotated in an elliptical orbit for this purpose. Should the operator 24 desire to cause the plane to do an inside loop, it is merely necessary to raise the pole from the ground and hold it obliquely upwardly from the horizontal at substantially shoulder level and rotate the plane, causing the plane to do a succession of inside loops. When it is desired to release a bomb, the operator pulls his finger downwardly on the ring 116 causing the operating ring 120 to rise,

lifting the cord 84 upwardly to tilt the lower end 78 of the bomb releasing lever outwardly to release a single bomb 42, with its upper end 80 underlying the upper end of the next adjacent bomb to prevent more than one bomb dropping at a time. When the operator releases his finger from the ring 116, the return spring 108 pulls the operating rod 102 downwardly and the spring 88 again tilts the bomb releasing lever 78 so that its upper end 80 is withdrawn from the slot 68 of the next adjacent bomb 42, to cause the succession of bombs to drop downwardly, with the lower end 78 of the lever simultaneously closing the lower end 64 of the bomb rack 40 to support the line of remaining bombs in the bomb rack, with the lower bomb in a cocked position for firing on next manipulation of the ring 116.

With practice, a great deal of accuracy in the dropping of bombs can be developed.

It is apparent that I have provided a novel type of airplane toy having the novel foregoing modes of operation, with the various novel advantages and results hitherto described.

It is understood that my invention is not limited to the specific embodiment shown and that various deviations may be made therefrom without departing from the spirit and scope of the appended claims.

What I claim is:

1. A toy, comprising a pole of a height substantially greater than that of an operator, having a freely rotatable ring mounted on the upper end thereof, a model airplane and a cord attached to said ring and to the top of said airplane whereby the lower end of said pole may be rested on the ground, its upper end tilted and rotated by the hand of the operator to cause said airplane to take off from the ground and rotate around said pole and operator a substantial distance above the ground until it gains flying momentum, when said airplane may fly on said ring around the then erect upper end of said pole and land evenly or continue its flight on intermittent rotations of the upper end of the pole or by rotating said upper pole end in an elliptical orbit said plane may dive and climb in flight, a bomb rack vertically mounted within said airplane, a succession of bombs vertically superimposed on each other within said rack and manually movable means mounted on and connected to said pole and airplane for successively releasing a single bomb at a time from said bomb rack, said bombs being of cylindrical shape with an extended reduced centre portion and said bomb releasing means comprises a cylindrical bomb rack mounted vertically of said airplane body, of a diameter to receive a succession of vertically superimposed bombs therein having an open upper end and an open lower end terminating below said body and a slot substantially the height of 1½ bombs from the lower end thereof and adjacent the lower surface of the body, a releasing lever of the first class of a length substantially the distance between said rack lower end and slot substantially centrally pivotally mounted on said depending lower bomb rack end having a lower inwardly projecting arm adapted to underlie said lower bomb rack and to support the bombs, and an upper inwardly projecting arm movable into and out of said slot and in which the upper end of the pole is provided with an axial hole extending a distance downwardly therein having a reduced portion extending a substantial distance downwardly and a radial slot extending an equal distance axially of said pole, a cylindrical bearing having its lower end mounted within the enlarged portion of said hole and extending a distance above it having an outwardly flaring top, a ring rotatably mounted on said bearing between said enlarged top and pole and an eyelet mounted on said model airplane interior of the centre of gravity thereof along its radius of revolution and a cord connected to said ring and eyelet to support said airplane during its flight, a bomb operating rod extending axially through said pole bearing and axial hole, having a portion projecting radially outwardly through said axial slot and a portion extending axially downwardly to adjacent the height of the operator, spaced guide eyelets mounted on said pole for the axially extending lower rod end, a return spring connecting said radial portion and said upper eyelet, aligned eyelets mounted axially on said pole diametrically opposite said lower rod end with the upper eyelet a substantial distance above said lower rod end, a looped cord having

of the next adjacent bomb and spring means operable on release of said manually movable means to tilt said lever back to a position withdrawing said upper arm from said slot, permitting said next adjacent bomb to drop with its lower end abutting the lower end of the next adjacent bomb to retain it in a cocked position on said rack.

2. A toy, comprising a pole of a height substantially greater than that of an operator, having a freely rotatable ring mounted on the upper end thereof, a model airplane and a cord attached to said ring and to the top of said airplane whereby the lower end of said pole may be rested on the ground, its upper end tilted and rotated by the hand of the operator to cause said airplane to take off from the ground and rotate around said pole and operator a substantial distance above the ground until it gains flying momentum, when said airplane may fly on said ring around the then erect upper end of said pole and land evenly or continue its flight on intermittent rotations of the upper end of the pole or by rotating said upper pole end in an elliptical orbit said plane may dive and climb in flight, a bomb rack vertically mounted within said airplane, a succession of bombs vertically superimposed on each other within said rack and manually movable means mounted on and connected to said pole and airplane for successively releasing a single bomb at a time from said bomb rack, said bombs being of cylindrical shape with an extended reduced centre portion and said bomb releasing means comprises a cylindrical bomb rack mounted vertically of said airplane body, of a diameter to receive a succession of vertically superimposed bombs therein having an open upper end and an open lower end terminating below said body and a slot substantially the height of 1½ bombs from the lower end thereof and adjacent the lower surface of the body, a releasing lever of the first class of a length substantially the distance between said rack lower end and slot substantially centrally pivotally mounted on said depending lower bomb rack end having a lower inwardly projecting arm adapted to underlie said lower bomb rack and to support the bombs, and an upper inwardly projecting arm movable into and out of said slot and in which the upper end of the pole is provided with an axial hole extending a distance downwardly therein having a reduced portion extending a substantial distance downwardly and a radial slot extending an equal distance axially of said pole, a cylindrical bearing having its lower end mounted within the enlarged portion of said hole and extending a distance above it having an outwardly flaring top, a ring rotatably mounted on said bearing between said enlarged top and pole and an eyelet mounted on said model airplane interior of the centre of gravity thereof along its radius of revolution and a cord connected to said ring and eyelet to support said airplane during its flight, a bomb operating rod extending axially through said pole bearing and axial hole, having a portion projecting radially outwardly through said axial slot and a portion extending axially downwardly to adjacent the height of the operator, spaced guide eyelets mounted on said pole for the axially extending lower rod end, a return spring connecting said radial portion and said upper eyelet, aligned eyelets mounted axially on said pole diametrically opposite said lower rod end with the upper eyelet a substantial distance above said lower rod end, a looped cord having

one end thereof connected to said lower rod end having a portion thereof extending around diametrically opposite sides of said pole and extending jointly downwardly through said opposite aligned eyelets, and a finger engageable ring mounted on the lower end of said loop, a stop nut mounted on the upper end of said rod, a ring rotatably mounted on the upper end of said rod above said stop nut, said model airplane having a hole extending substantially vertically therethrough and a cord having one end connected to said rotatable rod ring extending outwardly to said airplane and downwardly through said airplane hole and its opposite end connected to the lower arm of the bomb releasing lever.

3. A toy, comprising a pole of a height substantially greater than that of an operator, having a freely rotatable ring mounted on the upper end thereof, a model airplane and a cord attached to said ring and to the top of said airplane whereby the lower end of said pole may be rested on the ground, its upper end tilted and rotated by the hand of the operator to cause said airplane to take off from the ground and rotate around said pole and operator a substantial distance above the ground until it gains flying momentum, when said airplane may fly on said ring around the then erect upper end of said pole and land evenly or continue its flight on intermittent rotations of the upper end of the pole or by rotating said upper pole end in an elliptical orbit said plane may dive and climb in flight, a bomb rack vertically mounted within said airplane, a succession of bombs vertically superimposed on each other within said rack and manually movable means mounted on and connected to said pole and airplane for successively releasing a single bomb at a time from said bomb rack, said bombs being of cylindrical shape with an extended reduced centre portion and said bomb releasing means comprises a bomb rack mounted vertically of said airplane body, of a width to receive a succession of vertically superimposed bombs therein having an open lower end terminating below said body and a slot substantially the height of 1½ bombs from the lower end thereof and adjacent the lower surface of the body, a releasing lever of the first class of a length substantially the distance between said rack lower end and slot substantially centrally pivotally mounted on said depending lower bomb rack and having a

lower inwardly projecting arm adapted to underlie said lower bomb rack and to support the bombs, and an upper inwardly projecting arm movable into and out of said slot and in which the upper end of the pole is provided with an axial hole extending a distance downwardly therein and a radial slot extending a distance axially of said hole, a bomb operating rod extending axially through said axial hole, having a portion projecting radially outwardly through said axial slot and a portion extending axially downwardly to adjacent the height of the operator, spaced guide eyelets mounted on said pole for the axially extending lower rod end, a return spring connecting said rod and a fixed point on said pole, aligned eyelets mounted axially on said pole diametrically opposite said lower rod end with the upper eyelet a substantial distance above said lower rod end, a cord having one end thereof connected to said lower rod end having a portion thereof extending downwardly through said opposite aligned eyelets, and a finger engageable ring mounted on the lower end of said cord, a stop nut mounted on the upper end of said rod, a ring rotatably mounted on the upper end of said rod above said stop nut, said model airplane having a hole extending substantially vertically therethrough and a cord having one end connected to said rotatable rod ring extending outwardly to said airplane and downwardly through said airplane hole and its opposite end connected to the lower arm of the bomb releasing lever.
